UNITED STATES PATENT OFFICE.

JOHN SLATER, OF HANLEY, ENGLAND.

DESIGN FOR A COVERED DISH.

SPECIFICATION forming part of Design No. 33,282, dated October 2, 1900.

Application filed September 8, 1900. Serial No. 29,462. Term of patent 7 years.

to all whom it may concern:

Be it known that I, JOHN SLATER, a subject of the Queen of Great Britain, residing at the borough of Hanley, in the county of Stafford, England, have invented and produced a new and original Design for a Covered Dish, of which the following is a specification, reference being had to the accompanying drawings, forming a part thereof.

In the said drawings, Figure 1 is a plan view of a covered dish, showing my design. Fig. 2 is a side view of the same.

A continuous border A, composed of figures resembling "x's" and "o's," is located near the brim of the dish, from which are hung pieces of chain-like ornamentation B of equal length and having their ends joined at the points of meeting with the border A. These chain-like ornaments consist of figures b, similar to the "o's" of the outer border A, connected to each other by oblong link-like figures b, and a central figure c at the lowest point in each piece, composed of four "o's" or circles surrounding a small "o" or dot.

The whole design forms a continuous band or border around the brim of the dish, the figures making up the same being raised or embossed thereon. A similar band or border A is located near the rim of the cover.

The handles D of the dish and D³ of the cover are leaf-like in form, with a central floral piece D² between the ends of the two side pieces D². From the points where the handle D³ joins the cover proceed scrolls E and an ornament F, resembling a flower with stem and leaves.

The base G of the dish is of undulating outline and is provided near its lower edge with ornaments similar to C, connected by other ornaments resembling A. The brim of the dish is of regular oval form, as indicated by the dotted line h, while the body H thereof assumes an undulating form as it approaches the base. The rim of the cover corresponds in outline to the upper portion of the body. The cover has a raised portion I at the center.

What I claim is—

The design for a covered dish substantially as herein shown and described.

Signed at Buxslew, in the county of Stafford, England, this 28th day of August, 1900.

JOHN SLATER.
